UNITED STATES PATENT OFFICE

2,538,374

GOLF CLUB CARRIER

William J. May, Spokane, Wash.

Application September 11, 1947, Serial No. 773,349

1 Claim. (Cl. 280—41)

1

My present invention relates to an improved golf club carrier of the type employed by golfers to carry their clubs and including wheels so that the weight of the clubs is borne by the carrier rather than on the shoulder of the player or his caddie.

Specifically the carrier of my invention consists in a preferably metal container having individual compartments for the golf clubs, also exterior flexible pockets for the golfer's sweater or other equipment.

In the accompanying drawings I have illustrated one complete example of the physical embodiment of my invention according to the best mode I have thus far devised, but it will be understood that various changes and alterations may be made in the exemplified structure within the scope of the appended claims.

In the drawings:

Fig. 1 is a perspective view of the carrier of my invention.

Fig. 2 is a view as at line 2—2 of Fig. 1.

Fig. 3 is a vertical sectional view, and

Fig. 4 is a view as at line 4—4 of Fig. 3.

Referring now to the drawings, I have illustrated the present preferred embodiment of my invention as including the metal wall of sheet material 2, the ends of which are secured to plates 6. A bottom plate 8 is flanged at 10 and secured to the container, and on this plate I provide a fiber board base 12 and a sponge rubber sheet 14 to cushion the drop of the clubs placed in the carrier.

Within the container I position the angular sheets 16 to form the compartments 18 and a cover 20 of leather has apertures 22 aligned with the compartments so that the various clubs may be inserted, shaft end first into the apertures and into the compartments to keep the clubs separated from each other.

An accordion-plaited leather or cloth pocket 24 is secured to the front wall of the container by rivets 26, and may be provided with a multiple closure fastener 28.

A bracket plate 30 is secured to the rear plate 6 of the container at 32 and has a bearing portion 34 drilled at 36 to receive the shaft 38 to which the yoke arms 40 are secured by nuts 42. Axles 44 for wheels 46 are secured in the ends of the arms.

The shaft 38 has recesses 48 for the pin 50 having a knob 52 and slidably in the collar 54 in the bearing portion and the spring 56 on the pin confined by collar 58 and cotter pin 60 urges the pin 50 into one of the recesses 48 to secure the yoke 55

2

arms and wheels in extended position as shown or folded for carrying as in an auto.

A handle 62 on shaft 64 is secured on the ear 66 on plate 68 on the plate 6 of the container and is retained on bolt 69 by wing nut 70.

The handle may obviously be adjusted to the proper angle for the player and may be folded against the container for transportation.

The entire assembly may be made of light weight material and will effectively decrease the burden of the player in carrying the clubs and equipment on his shoulder and will permit the easy carrying of the equipment from hole to hole by the player merely pushing the carrier over the golf course.

The bracket plates 30 and 68 may be omitted and suitable brackets substituted to secure the bag to any conventional cart for carrying golf bags.

Having thus fully described my invention what I claim as new and desire to secure by Letters Patent is:

In a golf club carrier, the combination with a container having an adjustable handle, a bracket having a horizontal bearing bore, and means for attaching the bracket to the exterior of the container, of a rock shaft journaled in the bearing bore and having peripheral recess-sockets therein, a spring-pressed pin mounted in the bracket for selective engagement with the recess-sockets, a pair of yoke-arms rigid with the ends of the rock shaft, axles mounted in the free ends of the yoke-arms, and a pair of wheels journaled on said axles.

WILLIAM J. MAY.
